UNITED STATES PATENT OFFICE.

JOHN ALLEN WATSON, OF PERU, INDIANA.

LUGGAGE-CARRIER.

1,016,381.

Specification of Letters Patent.

Patented Feb. 6, 1912.

Application filed September 11, 1911. Serial No. 648,709.

To all whom it may concern:

Be it known that I, JOHN A. WATSON, a citizen of the United States, residing at Peru, in the county of Miami and State of Indiana, have invented a new and useful Luggage-Carrier; and I do hereby declare the following to be a full, clear, and exact description of the invention, such as will enable others skilled in the art to which it applies to make and use the same.

This invention relates to a new and useful carrier.

The principal object of the invention is to provide a device of this nature for carrying dress suit cases, show cases of traveling salesmen, or luggage or other commodities, in such manner as to remove the burden from the person.

A feature of the invention is the provision of a carrier, which may be adjusted in height, width and length, so as to fit cases or the like of various dimensions.

The invention comprises further features and combination of parts, as hereinafter set forth, shown in the drawings, and claimed.

In the drawings:—Figure 1 is a view in perspective of a luggage or commodity carrier constructed in accordance with the invention. Fig. 2 is a sectional view partly in elevation, showing the longitudinal adjustment of the carrier. Fig. 3 is a transverse sectional view partly in elevation, showing the transverse and vertical adjustments of the carrier. Figs. 4 and 5 are detail views.

Referring to the drawings 1 and 2 designate the longitudinal bars, which are constructed of two parts, arranged slidably with relation to one another. The longitudinal bars are provided with thumb screws, for holding the parts in adjusted positions.

These thumb screws are designated by the character 3. By making the longitudinal bars adjustable in this manner, the carrier may be adjusted to fit cases of different lengths. At each end of the longitudinal bars, transverse bars 4 and 5 are provided. These transverse bars consist of two adjustable parts 6 and 7, which parts are held in adjusted positions by the members 8. The longitudinal bars are provided with loops 9, through which the transverse bars pass, there being suitable thumb screws 10 passing through the loops, for holding the transverse bars adjusted with relation to the longitudinal bars.

The parts 6 and 7 of the transverse bars,

at their outer ends are provided with collars 12, which receive the uprights 11. Thumb screws 12^a and 10^c penetrate the collars, for holding the transverse bars adjustable upon the uprights. The lower portions of the uprights 11 receive the shanks 13 of the forks 14. The shanks 13 are in two parts, as shown hinged together at 13^d, so as to permit the forks to be folded. Journaled in 65 bearings of the forks are the stub axles of the wheels 15. These wheels may or may not be provided with pneumatic tires. To hold the shanks of the forks in adjusted positions thumb screws 16 are supplied.

Extending into the uprights 11 are the vertical members 17, which are held adjusted by the thumb screws 18. The upper end of one of the members 17 has hinged thereto as at 17^a a right angled extending 75 portion 19, which terminates in a loop 20, to receive the strap 21, which in turn connects to the loop 20^a of the link 19^a. This link 19^a is apertured at its free end as shown at 19^b, to receive the hook 19^c at the upper 80 end of the other member 17.

The outer ends of the two parts of the front transverse bar are adjustable on the uprights 22, by virtue of the collars 10^c and thumb screws 10^e. Extending into the upper portions of the uprights 22 are the members 23, which are held adjustable by the thumb screws or the like 24. The upper end of one of the members 23 has hinged thereto an extension 25^a, which terminates in a 90 loop 26. This loop 26 receives the strap 27, which in turn connects to the loop 26^a of the link 25. This link 25 has an eye 25^b, which receives the hook 25^c of the other member 23. Extending diagonally across one another, and connecting the diagonally disposed loops 20, 20^a, 26 and 26^a are the straps 28, which at their crossing points are provided with a holder 29. This holder is provided with a handle 30 to be gripped by 100 one's hand, whereby the carrier may be guided. By hinging the right angle extending portion 19 and the extension 25^a, and providing the links 19^a and 25 with the eyes to receive the hooks 19^c and 25^c, the 105 straps 21, 27 and 28 may be swung on the hinge connections between one of the members 17 and one of the members 23, and the right angled portion 19 and the extension 25^a. By this arrangement the luggage may 110 be arranged in the carrier without unbuckling the straps.

Extending downwardly from the forward transverse bar is a tubular extension 10^a, which receives the shank 13^a of the fork member 31. This shank is held in adjusted 5 positions by the thumb screw 16^a. The shank 13^a is constructed in two parts, hinged at 13^c. The forked member 31 has journaled therein the forward steering wheel 32. The upper end of the tubular 10 extension 10^a is formed with a collar 10^b, through which the thumb screw 16^a extends. This thumb screw engages a groove 10^c of the part 5 of the forward transverse bar, so as to hold the tubular extension in 15 its proper position relative to the forward transverse bar.

The outer ends of the two parts of the longitudinal bars terminate in short upwardly extending portions 33, between 20 which the suitcase or other luggage is arranged. One of the parts of each of the longitudinal bars and the transverse bars are provided with graduations 34, with relation to which the other parts of the longitudinal and transverse bars may be adjusted, whereby the parts may be arranged uniformly. 25

The fork of the front wheel 32 is provided with a swivel connection as shown at 36. 30 This swivel connection comprises the screw pin 31^c and the annular groove 31^b.

The shanks of the wheels 15 and the wheel 32, and the vertical members 17 and 23 are provided with graduations 38, designed for 35 the same purpose as those of the longitudinal and transverse bars.

From the foregoing it will be observed that there has been produced a novel, simple and efficient luggage or commodity carrier, 40 and one which has been found to be practicable.

The carrier may be provided with any number of wheels, while the structure of the

carrier may be changed to suit the contour and the make of the dress suit case or the 45 luggage.

The invention having been set forth, what is claimed as new and useful is:—

1. In combination, two part longitudinal and transverse bars, means for holding the 50 parts in adjusted positions, the transverse bars having vertical adjustable wheels, one of the wheels having a swiveled connection with relation to one of the transverse bars, the transverse bars having portions 55 extending upwardly from their ends, members received by the portions, and provided with means, to which transverse and diagonally disposed straps are connected.

2. In combination, two part longitudinal 60 and transverse bars, means for holding the parts in adjusted positions, the transverse bars having vertical adjustable wheels, one of the wheels having a swiveled connection 65 with relation to one of the transverse bars, the transverse bars having portions extending upwardly from their ends, members received by the portions, and provided with means, to which transverse and diagonally disposed straps are connected, the longitudinal 70 bars having loops through which the transverse bars pass, means penetrating the loops of the longitudinal bars for holding the transverse bars in adjusted positions, the outer ends of the longitudinal bars terminating into right angled upwardly extending portions, between which the commodity 75 is arranged.

In testimony whereof I have signed my name to this specification in the presence of 80 two subscribing witnesses.

JOHN ALLEN WATSON.
